F. NEWMAN.
FLUE CLEAN-OUT.
APPLICATION FILED JUNE 2, 1922.

Patented Nov. 7, 1922.

Fred Newman INVENTOR.

INVENTOR.

—ATTORNEY.

UNITED STATES PATENT OFFICE.

FRED NEWMAN, OF LOUISVILLE, KENTUCKY.

FLUE CLEAN-OUT.

Application filed June 2, 1922. Serial No. 565,500.

To all whom it may concern:

Be it known that I, FRED NEWMAN, a citizen of the United States, residing at Louisville, in the county of Jefferson and State 5 of Kentucky, have invented certain new and useful Improvements in Flue Clean-Outs, of which the following is a specification.

This invention relates to the clean-outs of chimneys or flues, and has for one of its objects to provide a simply constructed attachment whereby danger of the escape of ignited soot and cinders through the clean-out is obviated, and at the same time means provided for the easy removal of accumulations 15 of soot and ashes and the like.

With these and other objects in view the invention consists in certain novel features of construction as hereinafter shown and described and then specifically pointed out 20 in the claims, and in the drawing illustrative of the preferred embodiment of the invention:—

Figure 1 is a front elevation of the improved device.

Fig. 2 is a vertical section taken on the line 25 2—2 of Fig 1.

The improvement comprises a shell or casing 10 of sheet metal and adapted to be built in or inserted in an opening in a chimney or flue at the lowest possible point, the walls of the flue being indicated at 11. The shell 10 is preferably formed with an external flange 12 and internal flange 13, the external flange supporting an outer 30 closure or door 14, hingedly connected at 15 to the flange 12 and provided with a suitable catch 16.

Disposed within the shell 10, and preferably near its inner edge, is a combined cut-off and chute comprising a bottom portion 17 and side flanges or guards 18. The combined chute and cut-off is hinged at 20 to the bottom member of the shell 10 and when

in vertical position as shown in full lines in Fig. 2, completely closes the interior of the shell and forms an effectual cut off and coacts with the door 14, to effectually prevent the escape of any ignited soot, sinders or the like. The member 17 is provided with a handle 21 to facilitate its handling. 45 When the door 14 is opened, the cut-off member may be turned down into the position shown by dotted lines in Fig. 2 and thus form an effectual chute to facilitate the removal of soot and ashes from the chimney. 50

The preferred embodiment of the invention is disclosed in the drawing and set forth in the specification, but it will be understood that modifications within the scope of the claimed invention may be made in the 55 construction without departing from the principle of the invention or sacrificing any of its advantages.

Having thus described the invention what is claimed as new is:—

1. A device of the class described comprising a shell adapted to be set in an opening in a flue, a closure for the outer end of said shell, a combined chute and cut-off movably disposed within said shell and when 70 disposed in one position forming a guide means for the removal of ashes and soot through the shell.

2. A device of the class described comprising a shell adapted to be set in an opening in a flue, a closure for the outer end of said shell, a combined chute and cut-off hingedly connected to the bottom of the shell and extending beyond the outer face of the same when in lowered position to 75 form a guide means for the removal of ashes and soot through the shell.

In testimony whereof, I affix my signature hereto.

FRED NEWMAN.
